(57) **CLAIM**

The ornamental design for a wireless charger, as shown and described.

DESCRIPTION

FIG. 1 is a first perspective view of a wireless charger showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the wireless charger thereof; and,

FIG. 10 is a perspective view of another state of the wireless charger thereof.

The broken lines shown in the drawings depict portions of the wireless charger that form no part of the claimed design.

1 Claim, 10 Drawing Sheets
